UNITED STATES PATENT OFFICE.

WILLIAM T. THOMAS, OF GLENSIDE, AND HENRY T. PAISTE, OF PHILADELPHIA, PENNSYLVANIA, ASSIGNORS TO THE H. T. PAISTE COMPANY, INC., OF PHILADELPHIA, PENNSYLVANIA, A CORPORATION OF PENNSYLVANIA.

ADJUSTABLE OUTLET FOR ELECTRICAL APPARATUS.

995,203.

Specification of Letters Patent. Patented June 13, 1911.

Application filed March 9, 1910. Serial No. 548,277.

To all whom it may concern:

Be it known that we, WILLIAM T. THOMAS and HENRY T. PAISTE, citizens of the United States, residing in Glenside, county of 5 Montgomery, State of Pennsylvania, and Philadelphia, county of Philadelphia, State of Pennsylvania, respectively, have invented certain Improvements in Adjustable Outlets for Electrical Apparatus, of which 10 the following is a specification.

One object of our invention is to provide a relatively simple and easily adjustable attachment for the outlet openings of wall cabinets, outlet or junction boxes, 15 switch boxes, or other containers for electrical or other apparatus, whereby the size and if desired the shape of the opening to which the device is applied may be conveniently and rapidly changed or may be 20 closed altogether.

We further desire to provide an attachment for an opening of a container of the class above noted, which may be quickly adjusted to receive conduits, conductors, or bushings 25 of widely different shapes, and which while efficiently performing the functions for which it is designed, will occupy but relatively little space and be of a substantial nature.

30 These objects and other advantageous ends we secure as hereinafter set forth, reference being had to the accompanying drawings, in which:—

Figure 1, is a perspective view of a wall 35 cabinet or switch box showing our invention as applied thereto; Fig. 2, is a front elevation of a portion of one side of the box shown in Fig. 1, illustrating an opening therein as closed by our adjustable attachment; Fig. 3, is a perspective view of the adjustable outlet-closing or adjusting member, and Figs. 4, 5, and 6, are vertical sections illustrating the adjustable member in three of its possible positions.

45 In the above drawings, 1 represents a switch or cut out box usually formed of sheet metal and having in its sides any desired number of openings, of which one is indicated at 2.

50 The openings to which our invention is applied are usually though not necessarily, of a circular form and are intended for the reception of conduits, bushings, or insu-

lated conductors themselves. In order that it may be possible to form a tight joint between the conduit, bushing, or conductor and the wall or side of the box through which it passes, it is necessary that the opening in said side may be altered as to size, and in some cases, its shape also, for which purpose we provide an adjustable plate 3 preferably mounted on a pivot 4 on the inside of the box structure. In the present instance the pivot is provided by a screw 4, and the plate 3 itself is circular in form, 55 although it will be understood that its actual outline is immaterial. Said plate has formed in it a number of openings, indicated at 5, 6, and 7, and it is obvious that more or less than this number of openings 60 may be employed without departing from our invention. In addition there is provided in said plate a circular pressed-out or projecting portion 8, of such size and shape as to be capable of fitting into the 65 opening 2 in the side of the box, and the pivot screw 4 is so placed as to make it possible to bring any one of the openings 5, 6, or 7, or the pressed out portion 8, to a 70 position immediately adjacent and in line 75 with the opening 2. This latter is in the present instance of a diameter greater than that of any of the openings in the plate, and of these, the opening 6 is of U-shaped 80 form and extends inwardly from the edge 85 of the plate toward the center thereof; its width being somewhat less than that of the opening 2.

The opening 6 is in the present instance of circular form, of less diameter than the 90 opening 2, while the opening 5 has the shape of a figure eight, and is designed for the reception of a pair of twisted conductors or conduits. The opening 7, on the other hand, is designed to fit into the annular recess of 95 a bushing 9 of porcelain or other insulating material and in order to mount such a bushing in place, it is necessary to remove the plate 3 and after inserting it in the position shown in Fig. 4, to slide the plate into 100 position so that said bushing is retained in place by the edges of the opening 7. The screw 4 is then set up so as to hold the parts in place.

If it be desired to utilize one of the openings 5, 6, or 7, in the cases illustrated in

2
Figs. 4 and 6, the plate is mounted against the inside of the box so that its pressed out portion 8 extends away from the wall to which it is adjacent. When, however, it is desired to close the opening 2 in the side of the box, the plate is removed and reversed in position so that its pressed-out portion extends into said opening 2, as shown in Fig. 5.

10 It will be further noted that in order to close the opening 2 or to mount a bushing 9 therein, it is usually necessary to remove the plate, while if it be merely desired to alter the size or shape of the opening, the 15 screw 4 is loosened and the plate 3 is turned until the desired orifice is brought opposite said opening, after which the screw 4 is again set up.

We do not in this application claim an 20 outlet box having a plate adjustably mounted adjacent an opening therein and itself provided with an opening capable of co-operating with the opening in the box; the 25 plate being formed to fit into and close the box opening. Nor do we claim a box having an opening with a plate mounted adjacent said opening and provided with a substantially U-shaped recess capable of being brought into position to co-act with the 30 opening in the box, as well as having a portion capable of closing this opening, since these are described and claimed in an application for patent of Henry T. Paiste, Serial No. 459,425, filed Oct. 24, 1908.

35 We claim:—

1. The combination of a wall having an opening; with a plate adjustably mounted adjacent said opening and provided with

an opening capable of being brought into line with the opening of the wall; said plate 40 having a laterally projecting portion capable of fitting into and closing the opening of the wall.

2. The combination with a wall having an opening; a plate movably mounted adjacent 45 said opening and provided with a substantially U-shaped recess capable of being brought in line with the opening in the wall; said plate also having a laterally projecting pressed out portion capable of closing the 50 opening in the wall.

3. The combination with a wall having an opening, of a bushing mounted therein and provided with a recess, with a plate rotatably and removably mounted on the wall 55 and having a plurality of openings capable of being brought adjacent the opening in the wall; there being a portion of said plate capable of engaging the recess of the bushing to retain it in place.

4. The combination with a wall having an opening; of a reversible plate mounted adjacent said opening and provided with a laterally projecting portion capable of entering the opening of the wall; there being 65 an opening or openings in the plate capable of being brought into registry with the opening of the wall.

In testimony whereof, we have signed our names to this specification, in the presence 70 of two subscribing witnesses.

WILLIAM T. THOMAS.
HENRY T. PAISTE.
